UNITED STATES PATENT OFFICE.

HARRY R. DECKER, OF HOUSTON, TEXAS.

WELL-DRILLING MACHINERY.

No. 889,110.

Specification of Letters Patent.

Patented May 26, 1908.

Application filed November 8, 1906. Serial No. 342,532.

To all whom it may concern:

Be it known that I, HARRY R. DECKER, a citizen of the United States, residing at Houston, in the county of Harris and State of Texas, have invented certain new and useful Improvements in Well-Drilling Machinery, of which the following is a specification.

My invention relates to devices for drilling wells in alluvial deposits and known as rotary machines and has for its object the improvement of machines of the character described looking to adding thereto parts by which the machines may also be used for screwing and unscrewing casing and tubing.

15 The construction and operation of my improved device will be described hereinafter and illustrated in the accompanying drawings in which—

Figure 1 is a vertical sectional view of my improved machine in position for screwing or unscrewing casing, Fig. 2, a detail view of the casing support stand, Fig. 3, a top plan view of the jaws for clamping the casing, and Fig. 4, a plan view of the casing support stand.

In the drawings similar reference characters indicate corresponding parts throughout the several views.

The base of the rotary drilling machine is shown at 1 and has secured thereto the base plate or ring 2 formed with a raceway ring 3 in which are placed antifriction bearings 4.

5 indicates a rotary table having a raceway ring 6 to receive and seat on bearings 4, and formed with an annular groove 7 in its side to receive clamps 8 secured to base plate 2.

9 indicates a beveled gear face on table 5 and 10 a beveled gear wheel meshing therewith and keyed to drive shaft 11.

12 indicates the drill rod clamping jaws slidably mounted on the top of table 5 which may be of any desired construction. Adjacent to the outer edge of rotary table 5 are 45 ears 13 having holes or slots 14 therein.

15 indicates leg rests or seats secured to frame 1 and having sockets 16 therein to receive the bottoms of legs 17 of a table 18 having a central opening, said table being placed 50 around the casing or drill tube 19, when it is desired to screw or unscrew the tubing, by placing it in position surrounding the upper end of the casing or drill tube and then lowering it into the position as shown in the drawings.

55 20 indicates an upright post secured to

table 18 to which is secured any device for preventing the tubing or casing in the well from turning while the length of tubing or casing above is turned by the mechanism 60 hereinafter described.

In the drawings the device for preventing the tubing or casing from turning consists of a pair of pipe tongs 21 secured to coupling ring 19^a and with their handle engaging the 65 post 20, but it will be understood that any other device may be substituted for the pipe tongs if desired.

22 indicates an ordinary construction of elevator used in handling well tubes and casings.

It will be understood that when the casing in the well is held stationary, by the structure above described, the length of casing above the coupling ring 19^a may be screwed 75 or unscrewed by connecting it with a rotary table 5 and then rotating the table in the direction necessary to accomplish this. This may be done by securing another pair of tongs to the upper length of casing and providing a post or equivalent structure on the table 5, but I have found that a clamp, similar to that shown in the drawings, does the work more effectually.

The clamps shown in the drawings consist 85 of arms 23 having horizontal extensions 24 to fit into holes or slots 14 in ears 13.

25 indicates plates pivotally secured to arms 23 with disks 26 journaled therein to engage the tubing 19.

27 indicates rods pivotally secured in ears 28 on one of the plates 25 and adapted to seat in slots 29 in ears 30 on the other plate, the ends of said rods being screw-threaded as shown at 31 and 32 indicates nuts mounted 95 on said rods.

It will be understood that by screwing the nuts 32 up on the rods the disks are clamped into the tubing so that by rotating the table 5 and securing the coupling ring 19^a 100 the length of tubing 19 above ring 19^a is screwed into or unscrewed out of the ring, the disks 26 permitting longitudinal movement of the tubing while being turned.

Having thus described the invention what 105 I claim is—

1. In combination with a rotary for drilling wells, and tubing in the well, a ring-like table mounted in the rotary and surrounding the tubing and having legs, said legs being 110 secured independently of the rotary, means to connect the tubing and the ring-like table

to hold the tubing stationary, and means secured to the rotary to clamp the tubing, substantially as shown and described.

2. In combination with a rotary for drilling wells mounted on a base frame, and tubing extending through the rotary, socketed leg rests secured to said base frame, a ring-like table surrounding the tubing in the well and having legs resting in said socketed rests, 5 means to connect the ring like table and the tubing to hold the tubing stationary, and means secured to the rotary to clamp the tubing, substantially as shown and described.

3. In combination with a rotary for drilling wells, and tubing extending through the rotary, a ring-like table mounted in the rotary and surrounding the tubing and having legs secured independently of the rotary, a post secured on said table, means to connect 10 said post and tubing, to hold the tubing stationary, and means to secure one length of 15

the tubing to the rotary, substantially as shown and described.

4. In combination with a rotary for drilling wells mounted on a base frame, and tubing extending through the rotary, socketed leg rests secured to said base frame, a ring-like table surrounding the tubing in the well and having legs resting in said socketed rests or seats, a post secured to said table, means 20 to connect the tubing to said post to hold the tubing stationary, and clamping jaws removably secured to the rotary to clamp one length of the tubing and turn it simultaneously with the rotary, substantially as shown and de- 25 scribed.

In testimony whereof I hereto affix my signature in the presence of two witnesses.

HARRY R. DECKER.
